BICYCLE LOCK

Raymond N. Seaman, Randolph, Mass., assignor to Acme-Fab Industries, Inc., Stoughton, Mass.

Filed May 16, 1974, Ser. No. 470,336

Term of patent 14 years

Int. Cl. D8—07

U.S. CL. D8—114

FIG. 1 is an elevational view of a bicycle lock embodying my invention;

FIG. 2 is a view taken along the line 2—2 of FIG. 1;

FIG. 3 is a view taken along the line 3—3 of FIG. 2 with a section of the shackle broken away to show its cross-section; and

FIG. 4 is a view taken along the line 4—4 of FIG. 2.

I claim:

The ornamental design for a bicycle lock, as shown.
